GUIDE AND GUARD FOR PAINTBRUSHES

Fred D. Tamplin, Brookfield, Mo.

Application May 9, 1931. Serial No. 536,275

9 Claims. (Cl. 15—166)

This invention relates to a guide and guard especially adapted to be attached to paint brushes and the like, and has for its object the production of a simple and efficient guide and guard which 5 may be attached to the handle of a paint brush so as to facilitate the striping or lining of a surface, so as to permit the operator of the brush to draw or paint a straight and accurate line upon a surface through the medium of the specially designed guard and guide which is attached to the brush.

Another object of this invention is the production of a simple and efficient guide which is attached to the side of a brush so as to shield the 15 adjacent surface and permit the brush to only contact with the desired surface which is to be painted.

Another object of this invention is the production of a simple and efficient roller or guide which 20 will permit the brush to be held in a steady position and drawn over a surface in order to paint straight and accurate lines.

A still further object of this invention is the production of a simple and efficient guard which 25 may overhang the edge of a surface to be painted and permit the brush to only contact with the desired surface which is to receive the paint.

With these and other objects in view, this invention consists of certain novel construction, 30 combinations and arrangements of parts as will be hereinafter described and claimed.

Figure 1 is a side elevation of a brush showing the guide and guard attached thereto;

Figure 2 is an edge elevation of the brush 35 shown in Figure 1, a portion of the brush and guide as well as guard being shown in section;

Figure 3 is a side elevation of a modified form of my invention;

Figure 4 is an edge elevation partly in section 40 of the structure shown in Figure 3;

Figure 5 is a side elevation of a further modified form of the invention, and

Figure 6 is a perspective view of a still further modified form.

Figure 7 is a perspective view of a modified form of the invention showing the projecting ends of the guard plate rolled to overhang the side edges of the bristles of a brush.

By referring to the drawing, it will be seen that 50 1 designates the handle of the brush provided with the usual bristles 2, which are carried by the head 3 of the brush. The guide which is used in connection with the present invention preferably consists of an elongated metallic neck 4 having the end thereof turned over or overlapped as indi-

cated at 5 through which a pin or other suitable fastening element 6 passes for the purpose of connecting the elongated metallic neck 4 to the brush. This elongated neck 4 preferably terminates at its lower end in a flared or widened guard 7, these 60 parts preferably being formed of sheet metal for the purpose of lightness of structure and reduction in cost of manufacture. This guard 7 is of suitable or desired width to suit the convenience of the operator and is adapted to guard or 65 shield the bristles 2 of the brush and hold the same against lateral spreading over and beyond the surface which is to be painted.

A wheel or protecting disc, constituting a guiding wheel, 8, is pivotally mounted as at 9 upon the guard 7, and preferably projects beyond the lower edge 10 of the guard 7 as clearly shown in Figure 1, so as to permit the wheel 8 to travel over the surface which is to be painted and constitutes 70 a support and steady means for facilitating the drawing of the brush over the surface in a straight line. This disc also acts as a supplemental guard to protect adjacent surfaces. For instance, in painting a floor board or trim the disc is run along the joint between the board or 75 trim and the wall with the brush projecting against the edge of the board or trim and the paint may be applied to the board in this manner without being spread onto the adjacent wall surface.

From the foregoing description it will be seen that a very simple and efficient means has been produced whereby the operator may grip the handle of the brush as well as the head 3, and also grip the neck 4 of the guard in order to hold the same in a proper position so as to cause the wheel 8 to contact with the surface over which the brush is to be drawn. Then by the operator drawing the brush over the surface, the wheel 8 will readily roll over or travel upon the surface 80 and permit the bristles 2 of the brush to contact with the surface and only paint that portion of the surface over which the bristles will be drawn. By means of this device, a very simple and efficient means has been produced to permit an ordinary layman or unskilled workman to draw a very accurate and straight line for the purpose of lining or striping a painted surface. The contact of the wheel 8 with the surface over 85 which the brush is drawn will permit the steady- 90 ing of the brush and prevent the shaking there- 95 of which would be likely to take place in the event that no such guide or support were used. The guard 7 will, during this operation, prevent the lateral spreading of the bristles and will tend to 100 105 110

hold the same in a proper straight relation in order to insure the marking of a straight line through the medium of the bristles carrying the paint.

5. In Figures 3 and 4 there is shown a modified form of the invention wherein the brush handle 11 carries the usual head 12, the head 12 supporting the usual bristles 13. A strap 14 is pivotally connected at 15 near the bottom of the handle 11 and extends over the head 12, and to the lower end of this strap or link 14 is pivotally connected a guard plate 16, which guard plate projects well beyond the sides of the bristles 13 and may be swung when desired to contact with 10 a surface or overhang the edge of a surface to permit a proper striping or lining of the surface through the medium of the bristles 13. A rotatably mounted wheel 17 is rotatably connected to the lower end of the link or strap 14 as indicated 15 at 18, and this wheel 17 projects beyond the lower surface 19 of the guard plate 16. The lower corner edges of the guard plate 12 are curved as indicated at 20 to permit the guard plate to easily slide over a surface should the 20 plate 16 become swung upon its pivot and come in contact with the surface over which the brush is moved.

In Figure 5 there is shown a further modified form of the invention wherein the guard comprises an elongated neck 21 which is pivotally connected as indicated at 22, to the handle 23 of the brush. The head 24 of the brush carries a pin or other suitable fastening means 25 which pin passes through a slot 26 formed in the elongated neck of the guard 21. With this form of the device, the pivotal connection 22 may, if desired, be omitted and the guard swung or supported on the pivot or screw 25. This permits the adjustment of the guard longitudinally of the brush in order to regulate the distance which the bristles project beyond the guard. This guard 21 is provided with a laterally flared lower end 27, one end thereof along the lower edge being offset as indicated at 28 to constitute a sliding shoe to grip or engage the surface over which the brush is drawn and this lower edge 28 is preferably on a line with the lower edge 29 of the guide wheel 30. This guide wheel 30 is pivotally mounted upon a suitable pin 31. The guard, at its lower 45 flared ends 27, is extended beyond the sides of the bristles of the brush as clearly illustrated in Figure 5.

In Figure 6 there is shown a further modified form of the invention, the brush being shown in dotted lines. This guard as illustrated comprises an elongated strap 32 which is provided with an aperture 33 at the upper end for the purpose of permitting the attachment of the strap 32 to the handle of the brush. A suitable notch 34 is formed intermediate the ends of the strap 32 and is adapted to receive a pin for locking the strap 32 in a set position against swinging movement upon the brush. The lower end of the strap 32 carries a laterally extending guard plate 35 which is pivotally connected to the lower end of the strap 32 and is provided with projecting ends 36 which are adapted to project beyond the sides of the bristles of the brush. A guide wheel 37 is pivotally secured upon the pin 38 which also passes through the guard plate 35 and the lower portion 39 of the guide wheel 37 projects preferably below the lower edge of the guard plate 35. The guard plate 35 however, may be swung to engage the side edge of the surface over which the brush may be drawn.

It should be understood that through the medium of the present structure illustrated and described in the drawing, a simple and efficient means has been produced for facilitating the painting or striping of window sashes and other similar inconvenient work which it is desired to strip or paint, the guard and guide facilitating the drawing of the brush over the edge of the surface and preventing the bristles from contacting with the glass pane, and spreading the paint over the glass. Other difficult and inconveniently located surfaces may also be very easily painted through the medium of the device illustrated. As shown in Figure 4 a special guide may be placed upon either side of the brush and in all the structures illustrated, the guide and guard may be duplicated so as to mount one on each side of the brush so as to cause the bristles to pass between a pair of parallel guards and guide wheels. It should further be understood that certain detail changes in the mechanical construction may be employed without departing from the spirit of the invention so long as these changes fall within the scope of the appended claims.

As shown in Figure 7 the ends 40 of the guard plate 41 may be bent around the sides of the bristles of the brush, and the guard plate may be so constructed as to have one or both of its ends bent so as to overhang the side edges of the 105 bristles.

Having described the invention, what is claimed as new is:

1. A brush attachment of the class described comprising a guard adapted to be secured to the brush and project down parallel with the sides of the bristles when the brush is drawn over the surface to be painted and an auxiliary guard disc rotatably mounted on said guard.

2. A brush attachment of the class described comprising a guard adapted to be secured to a brush and project parallel with the bristles of a brush, and a guide wheel secured to said guard and projecting below the lower edge of said guard.

3. A device of the class described comprising a guard, said guard comprising an elongated neck adapted to be secured to the handle of a brush, said neck terminating in a wide flared guard plate adapted to project beyond the edges of the bristles of a brush and adapted to extend parallel with the bristles of a brush to prevent the spreading of the bristles, and a guiding wheel pivotally mounted upon said guard and projecting beyond the lower edge of said guard.

4. A brush attachment of the class described comprising a guard, said guard comprising an elongated shank adapted to be pivotally secured to a brush, a guard plate pivotally secured to the lower end of said shank, said guard plate projecting beyond said shank and adapted to extend beyond the side of the bristles of a brush, and a pivotally mounted guide wheel secured to said shank and projecting below the lower surface of said guard plate.

5. A brush attachment of the class described comprising a guard, said guard comprising an elongated shank adapted to be secured to the handle of a brush, said shank provided with an elongated slot formed therein, means passing through said slot for anchoring said shank in engagement with a brush, said shank terminating at its lower end in laterally flared side portions to produce a guard plate, and a guide wheel car-

- ried by said guard plate and projecting below the lower surface of said guard plate.
6. A brush attachment of the class described comprising a guard, said guard comprising an elongated shank adapted to be secured to the handle of a brush, said shank provided with an elongated slot formed therein, means passing through said slot for anchoring said shank in engagement with a brush, said shank terminating at its lower end in laterally flared side portions to produce a guard plate, a guide wheel carried by said guard plate and projecting below the lower surface of said guard plate, the lower surface of said guard plate provided with an offset lower edge projecting downwardly and extending normally on a line with the lower edge of said guide wheel.
7. A brush attachment of the class described comprising an elongated shank provided with means for facilitating the pivotal connection of said shank with the handle of a brush, said shank provided with a notch formed in one side adapted to receive means for anchoring said shank against swinging movement upon a support, a guard plate pivotally connected to the lower end of said shank and projecting laterally from both sides thereof, and a guide wheel pivotally mounted for rotating movement upon said shank and extending down below the lower end of said guard plate.
8. A brush attachment of the class described comprising a guard plate adapted to be secured to a handle and project down parallel with the sides of the bristles, said guard plate being provided with projecting ends bent laterally and having the ends thereof extending substantially parallel with the guard plate and adapted to overhang the side edges of the bristles of the brush.
9. The combination with a brush, of a guard comprising a plate having an enlarged end positioned adjacent to the bristles, means for adjustably securing the plate to the brush, and a disc rotatably secured to the enlarged end of the plate.
